UNITED STATES PATENT OFFICE.

HARRY R. DECKER, OF BEAUMONT, TEXAS.

OIL-WELL DRILL.

SPECIFICATION forming part of Letters Patent No. 732,925, dated July 7, 1903.

Application filed February 21, 1903. Serial No. 144,387. (No model.)

To all whom it may concern:

Be it known that I, HARRY R. DECKER, a citizen of the United States, residing at Beaumont, in the county of Jefferson and State of 5 Texas, have invented a new and useful Oil-Well Drill, of which the following is a specification:

The invention relates to improvements in rotary oil-well drills for operating where the 10 formation is of an alluvial nature with sand and clay deposits and where it is necessary to rotate continuously a drill-pipe through which a continuous flow of water is maintained for removing from the well the sand 15 and clay ground or mixed up by the bit or rotary shoe of the drill-pipe.

In drilling wells strata containing oil and gas under heavy pressure are frequently encountered, and when drilled into the pressure 20 blows everything out of the hole, and the well flows uncontrolled until it spends its force or is choked off by sand, clay, or rocks. When a blow-out occurs where a well is being drilled by the rotary process, the fluid in the well 25 rushes out of the top of the casing last set through the space between the same and the drill-pipe and up through the rotary table into the derrick. If the pressure be strong enough, the drill-pipe is lifted and thrown through the 30 top of the derrick, causing it to break off in parts as it becomes too high to support itself. A blow-out usually ruins the well for deeper drilling, and when the well does not thoroughly 35 purge itself of the drill-pipe the portion remaining in the well must be removed at great expense and trouble. Many wells drilled in this manner produce much sand with the flowing oil and soon choke up, the output of sand being as great as forty per cent. in some cases. 40 The wells when drilled into the oil stratum are kept clean by the agitation of the drill-pipe and the uplift of the water from the pump, and in consequence thereof such wells flow oil naturally for a short time; but the stratum in 45 which the oil is found being of a loose sandy formation the incoming of the oil brings sand with it, and thus the well is soon choked up and ceases to produce oil, as though the sand stratum had never been drilled into. Furthermore, such wells when first drilled are kept 50 thoroughly cleaned by the agitation of the

drill-pipe and the removal or uplift of the loose sand by the water or oil which is pumped down into the bottom of the well through the drill-pipe, and these circumstances admit of 55 the well becoming a gusher or natural-flowing well. However, the flowing of the oil through the derrick-floor stops the machinery, and once the rotation or agitation ceases and the pumping stopped the incoming sand which 60 accompanies the oil begins its work of choking up the well.

The object of the present invention is to improve the construction of rotary oil-well drills and to provide simple, inexpensive, and 65 efficient means for effectually anchoring the drill-pipe within the well-casing and for preventing the oil from flowing out of the top of the well and interfering with the operation of the drilling apparatus and to control the flow 70 or output of the well and at the same time enable any excessive gushing tendency to be checked.

The invention also has for its object to enable sand and oil producing wells to be successfully drilled and operated and to provide means for enabling the sand of the stratum containing oil to be continuously agitated after a well has been drilled and to supply 75 an artificial lift where the natural pressure of 80 the oil and gas is insufficient to cause the sand and oil to flow from the well.

Another object of the invention is to provide means for preventing the drill-pipe from being blown out of a well adapted to engage 85 and coöperate with the couplings of sections of the drill-pipe and capable of permitting such couplings to pass into the well-casing without losing control of the well and the drill-pipe, whereby the drill-pipe is effectually prevented from being blown out of the well should 90 it be subjected to an excessive pressure at a time when the parts are being adjusted for introducing a coupling into the well-casing.

With these and other objects in view the invention consists in the novel construction and arrangement of parts hereinafter fully described, illustrated in the accompanying drawings, and particularly pointed out in the claims hereto appended, it being understood 100 that changes in the form, proportion, and minor details of construction within the scope

of the claims may be made without departing from the spirit or sacrificing any of the advantages of the invention.

In the drawings, Figure 1 is an elevation, partly in section, of a rotary oil-well drill constructed in accordance with the invention. Fig. 2 is an enlarged vertical sectional view of the upper portion of the well-casing, illustrating the construction for locking the drill- pipe in the well and for preventing the oil from flowing through the top of the casing. Fig. 3 is a horizontal sectional view on the line 3 3 of Fig. 2. Fig. 4 is a similar view on the line 4 4 of Fig. 2. Fig. 5 is a horizontal sectional view on the line 5 5 of Fig. 2.

Like numerals of reference designate corresponding parts in all the figures of the drawings.

Referring to the drawings, 1 designates a rotary drill-pipe arranged within a well-casing 2 and composed of sections of the usual length connected by couplings 3, which form exterior projections and are utilized in the present invention in locking the oil-well drill-pipe in the well-casing to prevent the former from being blown out of the well, as has usually been the case when a heavy pressure incident to a natural-flowing well or gusher is encountered. The drill-pipe is connected at its upper end with a water-swivel 4 and is supported in the usual manner by a cable 5. The water-swivel is connected by a flexible pipe 6 with one of a pair of stand-pipes 7 of a pump 8, a pair of stand-pipes being designed to be provided in the usual manner to permit the parts to be readily coupled and uncoupled in supplying sections to the drill-pipe to increase the length of the same. The drill-pipe is rotated in the usual manner by a rotary table 9, supported above the floor of the derrick and operated by a suitable gearing. As this construction is the one in common use in rotary drills, a detail description of the same is unnecessary.

The well-casing is provided with a lateral outlet, preferably formed by a T-coupling 10, which is connected with a discharge-pipe 11, provided with a valve 12 and arranged to empty into a tank 13 or the like in the ordinary manner to permit the water discharged from the well during the drilling operation to be used over again. The discharge-pipe is also adapted to be connected with storage-tanks or other receptacles for storing oil flowing from the well after the drilling operation has been completed. The valve enables the flow or output of the well to be controlled, as will be readily understood.

The upper end of the well-casing is exteriorly threaded at 14 to engage interior screw-threads of a sectional body or casing 15 of a closure or oil-saver, which is provided with a bearing for the rotary drill-pipe, a stuffing-box for preventing the escape of oil or water or gas, and means for preventing the drill-pipe from being blown out of the casing when the same is subjected to the pressure incident

to the starting of a gusher or natural-flowing well. The casing or body 15 is composed of two semicylindrical sections provided at opposite sides with perforated flanges or ears 16 and connected by bolts 17 or other suitable fastening devices adapted to permit the sections to be readily placed around a drill-pipe and removed therefrom, if desired. The ends 18 and 19 at the top and bottom of the casing or body 15 are interiorly threaded, the lower end being screwed upon the upper end of the well-casing, as clearly illustrated in Fig. 2 of the accompanying drawings. The body or casing 15 is provided near its top with a horizontal supporting flange or partition 20, formed of sections and dividing the interior of the body or casing 15 into upper and lower compartments 21 and 22. The upper compartment 21 receives suitable antifriction devices for engaging the rotary drill-pipe to form a bearing for the same, and these antifriction devices are adjustable and adapted to be drawn outward to permit a coupling of the drill-pipe to pass into the body or casing 15. The antifriction devices preferably consist of balls 23, arranged in suitable grooves of adjustable blocks or sections 24. The grooves form a ball-race, and the blocks or sections, which are adapted to slide inward and outward in the upper compartment, are controlled by screws 25, piercing the opposite walls of the body or casing and provided at their outer ends with suitable heads or grips for enabling them to be conveniently rotated.

The stuffing-box, which is located within the lower compartment of the body or casing 15, consists of a sectional metallic gland 26, provided with upper and lower horizontal flanges and receiving a suitable packing 27, which is arranged between the flange and which engages the drill-pipe, as clearly shown in Fig. 2. When the packing is in contact with the drill-pipe, the flanges at the top and bottom of the gland are spaced from the said drill-pipe and the lower flange is arranged above the adjacent coupling and projects over the plane of the same to form a stop for engagement with the coupling 3 to prevent the drill-pipe from being blown out of the well-casing. The sections of the gland are engaged by opposite screws 28, which pierce the lower portions of the opposite walls of the body or casing 15 and which are provided at their outer ends with suitable heads or grips. In the accompanying drawings the body or casing 15, the device for supporting the antifriction-balls, and the gland are composed of semicircular sections; but they may be constructed in any other desired manner and may consist of a greater number of sections. The drill-pipe-engaging device of the rotary table cuts into the surface of the pipe, leaving burs and rough portions, which might injure the packing of the stuffing-box but for the upper bearing, which engages the drill-pipe and smooths the exterior surface of the

same and prevents the packing from being injured.

The upper end of the body or casing 15 receives a drill-pipe-engaging device consisting of a sectional collar or bushing 29, having exterior screw-threads 30 and provided with perforated ears or flanges 31, receiving bolts 32 or other suitable fastening devices. The bolts permit a limited separation of the sections of the collar or bushing when the same is unscrewed from the upper end of the body or casing 15 to permit the said collar or bushing to be passed over a coupling of the drill-pipe. In practice the collar or bushing after being passed over the coupling will be fitted against the upper edge of the same to be supported thereby until the coupling passes into the body or casing 15 to admit of the reengagement of the collar or bushing 20 with the upper interiorly-threaded end 18. The bearings are moved backward when the collar or coupling of the drill-pipe is introduced into the casing or body 15, and the latter is designed to be of sufficient size to permit the collar or bushing 29 to be replaced while the coupling is in the upper portion of the casing or body 15 and before the said coupling reaches the stuffing-box. After the collar or bushing has been replaced in the upper end of the body or casing the sections of the stuffing-box are drawn outward or released and permitted to move outward to allow the coupling to pass into the well-casing. After the coupling has entered the well-casing the sections of the stuffing-box are adjusted to engage the drill-pipe. This construction enables a stop or locking device to be maintained in operative position at all times for preventing the drill-pipe from being blown out of the well-casing should it encounter a heavy pressure at a time when the coupling is being introduced into the upper end of the well-casing. The stuffing-box and the rotary antifriction devices permit a free rotation of the drill-pipe; but the pressure may be increased to the desired extent to prevent leakage under abnormal conditions.

The drill-pipe is provided at its lower end with the ordinary fish-tail bit or rotary shoe 33, and as a well is drilled water is introduced into the hole through the aperture of the fish-tail bit or shoe, and the sand, clay, and other accumulations are carried upward by the water, and the well is maintained thoroughly clean during the drilling operation and while the pump is in operation. The drill-pipe is designed to remain in a well for use as a rotary agitator after the well has been completely drilled, and the operating mechanism indicated in the accompanying drawings may be employed as the motive power for rotating the drill-pipe for operating the well; but any other means may be substituted for the apparatus illustrated in the accompanying drawings to provide a simple and less expensive means for effecting this

result. When the pressure diminishes within the well and is insufficient to flow the oil, an artificial lift may be provided by introducing any aeriform fluid under pressure into the well by means of the drill-pipe. This fluid may consist of compressed air, or gas may be utilized, it frequently happening that a gas-producing well is accessible for this purpose. The apparatus will also permit a well to be otherwise treated, it being sometimes advisable to introduce water under pressure for forcing back oil and gas for preventing any tendency to gush. Also it frequently happens in this class of well-drilling that strata of oil containing sand are passed through without knowledge of the fact, the pressure of the water preventing a flow of oil and the hole becoming coated with mud in the usual manner; but with the apparatus herein described and shown these oil-containing strata can be worked and may be ascertained by inspecting the discharge from the lateral opening of the casing. In boring through a stratum of oil containing sand a quantity of oil is discharged with the water and may be seen as it appears in a rainbow streak or scum at the surface as it floats on the surface of the pool or tank into which the discharge-pipe empties.

When it is desired to introduce air under pressure into a well, the drill-pipe or rotary agitator is connected with a suitable air-compressor, or, in other words, an air-compressor may be substituted for the pump shown in the accompanying drawings.

The present invention is also especially designed and adapted for operating that class of wells which are at the present time abandoned owing to the excessive per cent. of sand, which with the present apparatus clogs up the well when the pressure is insufficient to produce a flow of the oil and sand and which when the pressure is sufficient for this purpose either produces an excessive overflow and prevents an operation of the apparatus, and thereby chokes up the well or forms a gusher and blows the drill-pipe out of the well-casing. With the present invention such a result is impossible, as the drill-pipe is securely locked within the well-casing, which is closed at the top and which is provided with a valved outlet. Also a continuous flow of oil and sand in low-pressure wells may be produced by simultaneously agitating the oil containing sand and introducing a fluid under pressure to produce an artificial lift. By this means many abandoned wells may be advantageously operated and oil obtained in paying quantities.

Should the presence of oil be discovered, the water is clarified and is then rarefied by mixing it with air under pressure. This will permit the oil to flow to enable it to be ascertained whether it is there in paying quantities without the necessity of setting the casing and bailing the well.

What I claim is—
1. In an apparatus of the class described,

- the combination with a rotary drill-pipe, and a well-casing closed at the top and provided with a lateral opening, of means for securing the drill-pipe within the well-casing to prevent the former from being blown out of the latter, substantially as described.
2. In an apparatus of the class described, the combination with a rotary drill-pipe, and a well-casing receiving the drill-pipe and closed at the top and provided with a lateral outlet, of a locking device comprising a stop connected with the well-casing, and means carried by the drill-pipe for engaging the stop, whereby the said drill-pipe will be prevented from being blown out of the well-casing, substantially as described.
3. In an apparatus of the class described, the combination of a rotary drill-pipe provided with couplings forming exterior shoulders, a well-casing receiving the drill-pipe and closed at the top and provided with a lateral outlet, and a stop carried by the well-casing and arranged in the path of the shoulders of the drill-pipe, whereby the latter is retained in the well-casing, substantially as described.
4. In an apparatus of the class described, the combination of a rotary drill-pipe provided with exterior shoulders, a well-casing closed at the top and provided with a lateral opening and receiving the drill-pipe, and a locking device carried by the well-casing and arranged to be engaged by the said shoulders to prevent the drill-pipe from leaving the well-casing, substantially as described.
5. In an apparatus of the class described, the combination of a rotary drill-pipe provided at intervals with couplings, a well-casing closed at the top and having a lateral opening, and upper and lower locking devices arranged in the path of the couplings and movable therefrom independently of each other to permit a coupling to pass them without releasing the drill-pipe, substantially as described.
6. In an apparatus of the class described, the combination of a rotary drill-pipe, a well-casing receiving the drill-pipe and closed at the top and provided with a lateral outlet, means for preventing the drill-pipe from leaving the well-casing, means for rotating the same, and means for introducing a fluid under pressure into the drill-pipe simultaneously with the rotation thereof, substantially as described.
7. In an apparatus of the class described, the combination of a well-casing closed at the top and provided with a lateral outlet, a rotary agitator, means for locking the rotary agitator within the well-casing, means for operating the agitator, and means for introducing a fluid under pressure into a well simultaneously with the rotation of the agitator, substantially as described.
8. In an apparatus of the class described, the combination of a well-casing having a lateral outlet, a drill-pipe arranged in the well-casing and provided with exterior shoulders, and a closure for the upper end of the well-casing, said closure being provided with means for engaging the shoulders of the drill-pipe and having a bearing for the same, substantially as described.
9. In an apparatus of the class described, the combination with a well-casing, and a rotary drill-pipe provided with exterior shoulders, of a closure for the upper end of the well-casing comprising a hollow body, an adjustable bearing provided with antifriction devices, and a combined stuffing-box and locking device engaging the drill-pipe and normally located in the path of the shoulders, substantially as described.
10. In an apparatus of the class described, the combination with a well-casing, and a drill-pipe provided with couplings, of a closure for the upper end of the well-casing comprising a hollow body, a sectional stuffing-box adjustably mounted within the hollow body and normally arranged within the path of the couplings, a sectional bearing provided with antifriction devices and located within the hollow body, and means for adjusting the sections of the stuffing-box and the bearing, substantially as described.
11. In an apparatus of the class described, the combination with a well-casing, and a drill-pipe, of a closure for the top of the same comprising a hollow body provided with upper and lower compartments, a sectional stuffing-box arranged in one of the compartments, a sectional bearing located in the other compartment, means for adjusting the sections of the bearing and the stuffing-box, and a locking device for engaging the drill-pipe, substantially as described.
12. In an apparatus of the class described, the combination with a well-casing, and a drill-pipe, of a closure for the top of the well-casing provided with a locking device comprising a sectional collar or bushing, substantially as described.
13. In an apparatus of the class described, the combination of a well-casing, a drill-pipe having exterior shoulders, a closure arranged at the upper end of the well-casing and provided with interior screw-threads, a sectional collar or bushing having exterior screw-threads for engaging the threads of the closure, and means for connecting the sections of the collar or bushing, substantially as described.
14. In an apparatus of the class described, the combination of a well-casing having a lateral outlet, a drill-pipe provided with couplings, a closure for the upper end of a well-casing comprising a hollow body, an adjustable bearing having antifriction devices, and an adjustable stuffing-box and a sectional collar or bushing detachably secured to the hollow body, said collar or bushing and stuffing-box being normally located in the path of the couplings, substantially as described.
15. In an apparatus of the class described, the combination of a rotary drill-pipe, a well-

casing receiving the drill-pipe and closed at the top and provided with a lateral outlet, means for rotating the same, and means for introducing a fluid under pressure into the 5 drill-pipe simultaneously with the rotation thereof, substantially as described.

16. In an apparatus of the class described, the combination of a well-casing closed at the top and provided with a lateral opening, a 10 rotary pipe arranged within the well-casing, means for rotating the pipe and means for introducing a fluid under pressure into the pipe to provide an artificial lift, and a bearing arranged at the top of the well-casing, 15 substantially as described.

17. In an apparatus of the class described, the combination of a well-casing closed at the top and provided with a lateral opening or outlet, a pipe located within the casing, means 20 for introducing a fluid under pressure into the pipe, and means for simultaneously actuating the same to agitate the sand at the bottom of the well, substantially as described.

18. In an apparatus of the class described, 25 the combination with a well-casing and a rotary drill-pipe, of means for locking the drill-pipe against vertical movement to prevent the same from being blown out of the casing, substantially as described.

30 19. In an apparatus of the class described,

the combination with a well-casing, of a rotary drill-pipe, arranged within the well-casing and provided with couplings forming exterior shoulders, and means for engaging the couplings for preventing the drill-pipe from being 35 blown out of the casing, substantially as described.

20. In an apparatus of the class described, the combination of a well-casing having a lateral outlet, a rotary drill-pipe, a closure for 40 the top of the casing provided with a bearing for the drill-pipe, means for introducing a fluid under pressure into the pipe, and means for simultaneously rotating the same to agitate the sand at the bottom of a well, sub- 45 substantially as described.

21. In an apparatus of the class described, the combination of a well-casing having a lateral outlet, a rotary drill-pipe provided with 50 couplings forming shoulders, and a closure for the top of the well-casing provided with a bearing arranged in the path of the couplings, substantially as described.

In testimony that I claim the foregoing as my own I have hereto affixed my signature in 55 the presence of two witnesses.

HARRY R. DECKER.
